HEARING AID APPARATUS

William D. Penn, Dallas, Tex.

Application June 26, 1936, Serial No. 87,537

3 Claims. (Cl. 179—107)

This invention relates to a new and improved apparatus used in aiding hearing and more particularly to a method and device for obtaining a frequency selective amplifier for use in aiding hearing of the partially deaf. An object of this invention is to provide an apparatus that may be used in aiding hearing and which is adapted to amplify selected frequencies.

Another object of this invention is to provide a hearing aid apparatus in which the frequency response characteristic may be controlled by means of an electromagnetic device, such as a transformer or a choke coil, the frequency characteristics of which may be controlled or adjusted.

Still another object of this invention is to provide a hearing aid apparatus with an electromagnetic device which is adapted to control the frequency response of said apparatus and which is adapted to attenuate certain predetermined selected audio frequencies depending upon the hearing deficiencies of the partially deaf user.

A further object of this invention is to provide a hearing aid amplifying apparatus adapted to attenuate certain selected audio frequencies or bands of audio frequencies depending upon the hearing deficiencies of the hard of hearing or partially deaf user.

Still a further object of this invention is to provide a hearing aid device adapted to be used by persons afflicted with partial deafness, said hearing aid device employing an electromagnetic apparatus having a plurality of windings, each of said windings being adapted to function to attenuate certain frequencies or bands of frequencies to which the hard of hearing user is the most sensitive.

Other and further objects of this invention will be apparent to those skilled in the art to which it relates from the following specification and the claims.

In accordance with this invention I provide a circuit arrangement adapted to be used in hearing aid apparatus, employing an electromagnetic device, such as a transformer, in which one or more windings are employed to attenuate one or more frequencies or bands of frequencies the level of which it is desired to reduce.

The apparatus of my invention is simple in construction and may be easily and readily made to fulfil the needs of persons afflicted with partial deafness. The apparatus of my invention may be made to attenuate certain frequencies or bands of frequencies, depending upon the nature of the deafness with which the user is af-

flicted, and may be adjusted and altered from time to time to suit the needs of the user, as his needs may change.

This is accomplished by providing a transformer or electromagnetic device, having one or more secondary windings to which are coupled devices which select the frequencies or bands of frequencies which are to be attenuated. By altering or changing the characteristics of these latter devices, the frequencies or bands of frequencies to be attenuated are changed. Where it is desired to change only one frequency band which is to be attenuated, this may likewise be done with equal facility.

Further details of this invention will be apparent to those skilled in the art to which it relates, from the following specification and the drawing, in which, briefly, Figure 1 illustrates an embodiment of this invention; Figures 2 and 2a illustrate another embodiment of this invention and Figure 3 shows an electrical network employed for the purpose of explaining the operation of this invention.

Referring to Figure 1 of the drawing in detail, reference numeral 10 designates a sound pick-up device, such as a microphone, a sound record reproducing device, and the like, connected to the primary 11 of a transformer 12 and to a suitable source of current supply 14. The secondary 13 of the transformer is connected to the grid electrode of the electric discharge device 15 and to a C battery 16 which is connected to the cathode of the electric discharge device. A suitable source of current supply 11 is provided for energizing the anode of the electric discharge device amplifier 15. The anode of the device 15 is connected to the impedance winding 18 which is shunted across the output terminals 19 of the amplifier. The impedance 18 is provided with two additional circuits coupled to the core thereof for the purpose of altering the frequency characteristic of this impedance device. These additional windings are designated as 20 and 21 and they may be wound on the core 22 of the impedance device in various ways depending upon the results desired. These windings 20 and 21 may be wound over the winding 18 so as to be concentric therewith and may be movable with respect to the winding 18 in order to be positioned over different sections of the latter winding. The terminals of the windings 20 and 21 are connected to suitable impedances 24 and 25 respectively. The nature of these impedances will govern the effective impedance between the

- terminals 1 and 2 of the impedance 18. The power delivered to the output device connected to the terminals 19, will depend upon the effective impedance of the device 18 which is shunted across said output terminals, and by properly proportioning the various windings 18, 20, and 21 and connecting suitable impedances 24 and 25 thereto, the response frequency characteristic of the hearing aid apparatus of this invention can be controlled as desired. Where convenient and desirable to obtain further variation in the frequency response characteristic, an additional impedance or impedances may be connected to the taps 18a and 18b of the impedance 18, or the 10 output circuit may be connected to these taps directly.

In the circuit diagram shown in Figure 1 the anode current of the electric discharge device amplifier 15 obtained from the source of current supply 17 passes through the winding 18 or through this winding and the output device connected to the terminals 19. This current may be prevented from flowing through the impedance winding 18 by connecting resistance 20 across this winding between the source of current supply 17 and the anode of the device 15 and by inserting a suitable blocking condenser between this resistance and one of the terminals of the winding 18. This will prevent the anode 25 current derived from the source 17 from passing through the winding 18 in cases where it is desired to prevent this anode current from magnetizing the core of this impedance device.

The windings 20 and 21 may be wound each 30 with a different number of turns or each with a different inductance. Each of these windings may be tuned by means of suitable condensers to be resonant to certain audio frequencies and to absorb power at said frequencies from the 35 circuit of the winding 18. Thus the frequency characteristic of the hearing aid device may be varied, depending upon the characteristics of the impedance device. Furthermore the resonance characteristics of the circuits of the windings 20 and 21 may be broadened if desired in 40 one or both of these windings to cover a relatively broad band of frequencies, by connecting a resistance of suitable size in series with each 45 of these windings.

In Figures 2 and 2a I have shown the impedance winding 18 connected between the microphone or other sound pick-up device and a reproducing device 28, without the use of an electric discharge device amplifier. The operation 50 of this impedance device in these cases is similar to that of the arrangement shown in Figure 1, except that in Figure 2 the windings 20 and 21 are positioned endwise on an elongated core 22 and the coupling between these windings 20 and 21 and the winding 18 may be varied either by moving the windings 20 and 21 away from the winding 18 or by moving the core 22, to obtain the desired frequency response characteristic.

The operation of the hearing aid of this invention, in cases where the windings 18, 20, and 21 of the impedance device are closely coupled may be determined from the following when considered with the equivalent electrical network shown in Figure 3.

For the general case of a transformer with a mutual impedance

$$Z_m = k\sqrt{X_1 X_2}$$

between primary and secondary windings the

impedance looking into the primary winding of the device is

$$Z_{12} = R_1 + \frac{Z_m^2 R_2}{Z_1^2} + j \left(X_1 - \frac{Z_m^2 X_2}{Z_1^2} \right) = R_1 + \frac{k^2 X_1 X_2 R_2}{R_1^2 + X_1^2} \quad 5$$

In the above equation:

R_1 = Resistance of primary winding.

R_2 = Resistance of secondary circuit including resistance component of load.

X_1 = Reactance of primary winding.

X_2 = Reactance of secondary winding.

Z_1 = Total reactance of secondary circuit.

$$Z_m = k\sqrt{X_1 X_2}$$

k = Co-efficient of coupling.

$Z_1 = R_1 + jX_1$ = total secondary impedance.

The equation shows that for any given coefficient of coupling k the impedance looking into the primary is a function of the load impedance connected to the secondary. The impedance Z_{12} here corresponds to the impedance designated as Z_1 in the case of the closely coupled transformer.

For a closely coupled transformer, Z_1 is equal to the quantity n_1 divided by n_2 squared, times Z_2 . Where n_1 is the number of turns in the primary of the device 18 and n_2 is the number of turns in the secondary of this device. Z_2 is the impedance in ohms of the impedance device connected to the aforesaid secondary. If Z_2 is a pure resistance then the effect of connecting it across the winding n_2 is in effect the same as shunting the output device of impedance Z_r with a resistance.

If Z_2 is an inductance L_2 , for example, the effect of connecting it across the winding n_2 is the same as shunting Z_r with an inductance equal to the quantity n_1 divided by n_2 squared, times L_2 . On the other hand, if Z_2 is a condenser the effect of connecting it across the winding n_2 is the same as shunting Z_r with a condenser equal to the quantity n_2 divided by n_1 squared, times C , C being the value of the condenser. If the transformer has more than two windings the impedance looking into any winding, called for convenience the primary winding, of a transformer having N windings is equal to the self-impedance Z_0 of the primary winding multiplied by the product of all the load impedances $Z_1, Z_2, Z_3, Z_4, \dots, Z_N$ to which the other or secondary windings are connected, and divided by the sum of the products of the various self impedances of the secondary windings $Z_2, Z_3, Z_4, \dots, Z_N$ and the various load impedances with which the different secondary windings are not directly associated. In Fig. 2, for instance, the impedance Z_1 looking into the winding 18 is

$$Z_1 = \frac{Z_0 Z_2 Z_3}{Z_2 Z_1 + Z_3 Z_1}$$

where Z_0 is the self impedance of winding 18, Z_2 is the self impedance of winding 20, Z_3 is the self impedance of winding 21, and Z_1 and Z_2 are as shown. The frequency attenuation caused by the shunt Z_1 depends upon the values of Z_0 and Z_2 , where Z_0 is the internal or output impedance of the source. In Fig. 1, Z_0 would be r_p the dynamic plate resistance of the vacuum tube, while in Fig. 2 and Fig. 2a, Z_0 would be the impedance of the microphone 10. The value of the impedance Z_1 depends upon the characteristics of the windings n_1 and n_2 and the effect of the impedance Z_2 . In general, if the effective shunt impedance of the winding Z_1 , including the effective impedance of the windings n_1 and n_2 and the impedance Z_2 , is represented by the

impedance Z_s , the power loss introduced into the circuit by the effective shunt impedance Z_s may be determined from the following equation which gives the power loss in decibels.

$$5 \quad N = 20 \log_{10} \left(1 + \frac{Z_o Z_r}{Z_s (Z_o + Z_r)} \right) \text{db.}$$

If impedance Z_s varies with frequency or if this impedance is fixed and either impedance Z_o or Z_r varies with frequency then the response is different at different frequencies, as may be determined from the aforesaid equation.

From the foregoing it will be observed that I have described particular embodiments of this invention in detail, however, various modifications within the spirit and scope of this invention may be made therein and I do not therefore desire to limit this invention to the exact details set forth except insofar as they are defined by the claims.

What I claim and desire to secure by Letters Patent of the United States is as follows:

1. A device for aiding hearing by attenuating frequencies to which a user of the device is normally sensitive, comprising an input device, an output device, an electromagnetic frequency attenuating device having a winding shunted across said output device and electromagnetic means for altering the frequency attenuating characteristics of said frequency attenuating device, said last mentioned means including one or more impedance circuits coupled to said frequency attenuating device for the purpose of introducing losses equal to

$$35 \quad 20 \log_{10} \left(1 + \frac{Z_o Z_r}{Z_s (Z_o + Z_r)} \right)$$

in decibels, where Z_o is the effective impedance in the circuit of said input device, Z_r is the impedance of said output device and Z_s is the effective shunt impedance of said frequency attenuating device, said losses being introduced at frequencies determined by the characteristics of said attenuating device for reducing the response of the hearing aid at these predetermined frequencies to which the user is normally sensitive to a level substantially below the normal response of the hearing aid to the remaining frequencies.

50 2. A device for aiding hearing by attenuating frequencies to which a user of the device is nor-

mally sensitive, comprising: a sound pick-up and translating device, a vacuum tube amplifier having an input and an output circuit, means for connecting said sound pick-up and translating device to said amplifier input circuit, a sound reproducing device connected to said amplifier output circuit, a frequency selective attenuating device comprising a main winding connected across said reproducing device, said frequency attenuating device having at least two auxiliary 10 windings coupled together, an impedance device connected to each of said auxiliary windings for altering the frequency characteristics of said attenuating device, said impedance devices connected to said auxiliary windings of said attenuating device being adjusted so that said attenuating device will absorb power from the circuit of said amplifier and from said sound reproducing device at frequencies determined by the characteristics of said impedance devices and said 15 windings for the purpose of reducing the response of the hearing aid at these predetermined frequencies, to which the user is normally sensitive, to a level substantially below the normal response of the hearing aid to the remaining 20 frequencies.

3. A device for aiding hearing by attenuating frequencies to which a user of the device is normally sensitive, comprising: a sound pick-up and translating device, a vacuum tube amplifier having an input circuit and an output circuit, means for connecting said sound pick-up and translating device to said amplifier input circuit, a sound reproducing device connected to said output circuit, a frequency attenuating device having a 30 main winding connected across said sound reproducing device and a pair of auxiliary windings coupled to said main winding, an impedance device connected to each of said auxiliary windings, each of said impedance devices forming a power 40 absorbing circuit with the auxiliary winding connected thereto, having predetermined frequency characteristics such that the hearing aid device may be adjusted to meet the deficiencies of partially deaf persons by selecting impedance devices 45 of such frequency characteristics that audio frequencies to which the partially deaf person is normally sensitive will be attenuated when the selected impedance devices are connected to said auxiliary windings.
